UNITED STATES PATENT OFFICE.

VERONICA HMENIA, OF KLEIN, MONTANA.

RUBBER THIMBLE.

1,380,960.

Specification of Letters Patent. Patented June 7, 1921.

Application filed March 23, 1920. Serial No. 368,182.

To all whom it may concern:

Be it known that I, VERONICA HMENIA, a citizen of Czecho-Slovakia, residing at Klein, in the County of Musselshell and State of Montana, have invented certain new and useful Improvements in Rubber Thimbles, of which the following is a specification.

This invention relates to elastic thimbles, and is especially designed for use in protecting the finger from the action of crocheting needles.

The principal object of the present invention is to provide an elastic thimble having a flexible tip and which is reinforced at the side thereof where the point of a crocheting needle is most liable to contact with the finger of the operator, so that the usual soreness of the finger following crocheting will be prevented and which will not interfere with the facile manipulation of the thread.

Furthermore, the present invention aims to provide improved means for removing the resilient thimble, and also to provide means for ventilating the interior of the elastic thimble.

For the purpose of illustrating this invention, there is shown in the accompanying drawings one form thereof which is at present preferred, since the same has been found in practice to give satisfactory and reliable results, although it is to be understood that the various instrumentalities of which the invention consists can be variously arranged and organized and that the invention is not limited to the precise arrangement and organization of these instrumentalities as herein shown and described.

In the drawings:

Figure 1 is a perspective view of the invention.

Fig. 2 is a sectional side elevation thereof.

Like characters of reference indicate like or similar parts throughout the several views of the drawings, in which:

The elastic thimble in its entirety, which is preferably constructed of rubber or the like is designated A and has formed on the rear portion thereof a projection in the form of a teat B for use in removing the thimble from the finger. Between the projection B and the terminal edge of the thimble is a series

of ventilating openings C, so positioned that all danger of the needle point entering one of them is prevented.

55

Referring particularly to Fig. 2 of the drawing as illustrated the tip of the thimble A is constructed of very thin rubber as designated by D while the sides E are formed of considerably thicker rubber, said thimble being provided at its open end with a reinforcing bead F. The purpose of these two thicknesses of rubber is that the point of the crocheting needle engages the side portion of the finger, and consequently it is necessary 65 to reinforce the thimble at that point and it is desirable that the tip be thin and flexible to provide for the facile manipulation of the thread. Attention is called to the fact that the front portion of the thimble presents a 70 plain surface while the rear portion, that is the portion upon the top of the finger, has the projection B and the openings for ventilating the interior designated by C.

In operation the thimble is placed upon 75 the finger with the plain surface thereof on the inner portion of the finger and with the projection B on the top or outside portion of the finger. During the operation of crocheting the point of the crocheting needle will 80 contact with the reinforced portion of the thimble, and consequently possible soreness of the finger will be prevented.

From the foregoing description taken in connection with the accompanying drawings, 85 it is thought that a clear and comprehensive understanding of the construction, operation and advantages of the invention may be had, but while I have shown and described the thimble as embodying a specific structure, I 90 desire it to be understood that such changes may be made in said structure, as do not depart from the spirit and scope of the invention as claimed.

What is claimed is:

95

A rubber crochet thimble having a thin flexible tip and thickened side walls with a laterally extending handle on the outer face of one of said side walls intermediate the ends thereof to facilitate removal of the 100 thimble from the finger.

In testimony whereof, I affix my signature hereto.

MRS. VERONICA HMENIA.
